(57) **CLAIM**

I claim the ornamental design for an improvised explosive device locator with telescoping handle, as shown and described.

DESCRIPTION

FIG. 1 is a perspective view of one embodiment of the head of the improvised explosive device locator with telescoping handle. The telescoping handle shown in broken lines is included to show environment and forms no part of the claim. FIG. 2 is a perspective view of the same embodiment of the head showing my new design enlarged.

FIG. 3 is a front elevational view thereof.

FIG. 4 is a first side elevational view thereof.

FIG. 5 is a second side elevational view thereof as seen from the side opposite that of FIG. 4.

FIG. 6 is a rear elevational view thereof.

FIG. 7 is a top plan view thereof; and,

FIG. 8 is a bottom plan view thereof.
